W. COX.

SCUDDING ATTACHMENT TO PELT AND HIDE WASHING OR BATING MACHINES.

APPLICATION FILED SEPT. 5, 1917.

1,305,774.

Patented June 3, 1919.

FIG.1

FIG.3

FIG.2

FIG.4

Inventor:
William Cox
of Arpabeton,
Mass.

UNITED STATES PATENT OFFICE.

WILLIAM COX, OF PETONE, WELLINGTON, NEW ZEALAND.

SCUDDING ATTACHMENT TO PELT AND HIDE WASHING OR BATING MACHINES.

1,305,774.

Specification of Letters Patent. Patented June 3, 1919.

Application filed September 5, 1917. Serial No. 189,720.

To all whom it may concern:

Be it known that I, WILLIAM COX, subject of the King of Great Britain, residing at Petone, Wellington, in the Dominion of

5 New Zealand, have invented a new and useful Scudding Attachment to Pelt and Hide Washing or Bating Machines; and I do hereby declare the following to be a full, clear, and exact description of the same.

10 This invention has been designed in order to provide an attachment for the well known construction of pelt and hide washing or bathing machines in which a rotating "dolly," or series of radiating beater arms, is employed to agitate the pelts or hides contained in the washing or bathing fluid. The object of the attachment is to subject the pelts or hides to a scudding treatment during the washing or bathing operation.

15 It is generally customary in the treatment of animal hides or pelts, in order to remove any flesh or other matter adhering to their surfaces, to subject them to a "scudding" or scraping operation usually performed by hand and by the employment of special scudder or scraper knives. The present invention dispenses with this hand treatment, and provides for the scudding or scraping operation upon the pelts, being performed during the

20 washing or bathing operations to which they are subjected in the machine referred to.

To effect the object of my invention a beater or scraping bar, formed with one or more edges extending longitudinally along its bottom, is so arranged within the tank of the machine as to extend in a position adjacent to the "dolly" so that in the rotation of the dolly the latter will cause the pelts or hides to be moved across the scraping edge 35 or edges of the attachment. The bar is preferably suspended within the machine in such a manner that it may be swung up out of use whenever required.

40 My invention is illustrated in the accompanying drawings, in which:—

Figure 1 is a cross sectional elevation of a machine with the attachment in position therein.

45 Fig. 2 is a front elevation thereof, the tank being shown in section.

Fig. 3 is a cross section, on an enlarged scale showing the construction of the beater or scraping bar and also the means for mounting it in the machine.

50 Fig. 4 is an elevation of an alternative form of scraper bar.

A is the washing tank and B the rotating "dolly" mounted therein. These are of the ordinary and well known construction.

5 C is the beater bar or scraping bar constituting this invention and which is formed in any suitable manner such as to provide one or more serrations or teeth D extending along its bottom edge. Two of these teeth are shown in the drawings in which the bar 60 represented is made of wood and the teeth provided with strips E of metal, such as steel secured along their faces to form the actual scraping edges. The working edges of these strips may be made plain as shown 65 in Fig. 2, or scalloped or serrated as shown in Fig. 4.

70 The bar is arranged parallel with and adjacent to the dolly B so that in the working thereof, the pelts or hides will be drawn across the edges or teeth and subjected to a scraping or scudding action such as to dispense with or reduce the separate scudding treatment to which such pelts or hides have at present to be afterward subjected.

75 As will appear from the drawing, the rotation of the dolly will cause its beaters to engage the hides or pelts, which are kept agitated and moving by the flow of water through the tank A, so that the beaters will 80 grip them and drag their surfaces across the scraping edge of the bar C.

85 It is well known that in the operation of these appliances a constant stream of water is led through the washing tank, entering 90 over the right edge (according to the drawings) and passing down around the bottom and overflowing the left edge. This serves to wash the pelts or hides toward the left edge. The dolly rotates in a reverse direction *i. e.* from left to right on the lower portion of its rotation so that its beaters grip the pelts or hides as they rise with the water current, and draw them across to the right 95 hand side again. These operations are continued repeatedly. The bar C then engages

100 the pelts or hides as they are gripped and drawn across by the dolly beaters, the upward floating action of the water current keeping them in contact with the scraping 105 edges D and the beaters dragging them across such edges. In this manner, the pelts or hides are scraped as desired.

110 The bar C is preferably so mounted that it may be swung up out of the way, when not required to be used, or when the machine is being filled or emptied. This is effected by

suspending it by means of straps F from the rod G that extends along the machine. The rod passes through the end plate of the machine at each end thereof and is supported in an adjustable bearing H so disposed and constructed as to permit of the rod being adjusted to any desired height. Each strap F is formed with an elongated eye F' through which the rod G passes so that the bar C may be raised and then turned up and over to rest upon the supports J on the insides of the respective machine ends, as indicated by the dotted lines in Fig. 1, whenever required. Stops K are also provided on the insides of such ends, to engage the bar C when it is down and prevent it swinging into contact with the dolly. If desired, each of the arms of the dolly B may be provided with a plate B' secured along its forward face and projecting beyond its edge so as to form a scraping edge. This edge may be sharpened and corrugated similarly to the plates E, and thus provide for the machine being used for de-hairing hides, as well as for the other purposes specified.

Copies of this patent may be obtained for five cents each, by addressing the "Commissioner of Patents, Washington, D. C."

I claim:—

1. Attachment for pelt and hide washing machines, comprising a bar arranged longitudinally of the machine adjacent to and parallel with the rotating "dolly" or beaters, such bar being formed with one or more scraping edges along its bottom, substantially as and for the purposes herein specified. 35
2. An attachment as specified in claim 1, in which the bar is suspended to hang upon a support carried by the machine so as to be swung into and out of operative position at will. 40
3. An attachment as specified in claim 1 in which a support is provided in the machine for maintaining the bar in its inoperative position out of the path of the operating parts of the machine. 45

In testimony whereof I have signed this specification in the presence of two subscribing witnesses.

WILLIAM COX.
